UNITED STATES PATENT OFFICE.

EDWARDS B. STUART, OF CHICAGO, ILLINOIS.

DESIGN FOR A FAUCET SET.

Application filed August 21, 1925. Serial No. 14,543. Term of patent 14 years.

To all whom it may concern:

Be it known that I, EDWARDS B. STUART, a citizen of the United States, residing at Chicago, county of Cook, and State of Illinois, have invented a new, original, and ornamental Design for Faucet Set, of which the following is a specification, reference being had to the accompanying drawing, forming part thereof,

The figure is a perspective view of a faucet set showing my new design.

I claim:

The ornamental design for a faucet set as shown.

E. B. STUART.
